(57) **CLAIM**

The ornamental design for an electromagnetic relay, as shown and described.

DESCRIPTION

FIG. 1 is a front view of a design for an electromagnetic relay according to the present disclosure.

FIG. 2 is a rear view of the electromagnetic relay of FIG. 1. FIG. 3 is a left side view of the electromagnetic relay of FIG. 1.

FIG. 4 is a right side view of the electromagnetic relay of FIG. 1.

FIG. 5 is a plane view of the electromagnetic relay of FIG. 1.

FIG. 6 is an enlarged view of the electromagnetic relay of FIG. 1 at the intersection of 6-6 in FIG. 5.

FIG. 7 is a bottom view of the electromagnetic relay of FIG. 1.

FIG. 8 is a reference perspective view of the electromagnetic relay of FIG. 1.

FIG. 9 is a reference perspective view of the electromagnetic relay of FIG. 1; and,

FIG. 10 is an enlarged view of the electromagnetic relay of FIG. 1 at the intersection of 10-10 in FIG. 8.

The broken line portion of the figure drawings is included to show portions of the electromagnetic relay that form no part of the claimed design.
